United States Patent Office

Des. 232,819

Patented Sept. 17, 1974

232,819

TIRE

Walter W. Hinkel, Massillon, and Philip S. Hammond,
Akron, Ohio, assignors to The Goodyear Tire & Rubber Company, Akron, Ohio

Filed June 25, 1973, Ser. No. 373,236

Term of patent 14 years

Int. Cl. D12—15

U.S. Cl. D12—142

The figure is a perspective view of a tire showing our new design, it being understood that the design is repeated throughout the circumference of the tire, the opposite side being substantially the same as that shown.

We claim:

The ornamental design for a tire, substantially as shown and described.
